UNITED STATES PATENT OFFICE.

BENJAMIN J. TAYMAN AND JOSEPH BENNOR, OF PHILADELPHIA, PENNSYLVANIA, ASSIGNORS, BY MESNE ASSIGNMENT, TO GEORGE H. P. FLAGG, OF BOSTON, MASSACHUSETTS.

MACHINE FOR FORMING IMITATION FAIR-STITCHES TO THE EDGES OF BOOT AND SHOE SOLES.

SPECIFICATION forming part of Letters Patent No. 234,503, dated November 16, 1880.

Application filed October 6, 1880. (Model.)

To all whom it may concern:

Be it known that we, BENJAMIN J. TAYMAN and JOSEPH BENNOR, both of Philadelphia, Pennsylvania, have invented an Improvement 5 in Machines for Forming Imitation Fair-Stitches on the Edges of Boot and Shoe Soles, of which the following is a specification.

The mechanism employed to effect the object in view is illustrated in the annexed drawings, in which—

Figures 1, 2, and 3 are respectively front, side, and rear elevations of the same. Figs. 4 and 5 are respectively face and sectional views, on an enlarged scale, of the impression-stitch wheel z , showing the rounded bevel a^2 for preventing the wheel-teeth from coming in contact with the boot or shoe upper while the impression fair-stitch is being impressed. Figs. 6 and 7 are respectively sectional and 20 top views of a burnishing-head with the said fair-stitching mechanism applied to it.

s and t are two levers, the lever s being attached by the screw u to a plate, v , which may be attached by screws to the bottom of 25 a burnishing-head, as shown. The lever s turns on the screw u as a fulcrum, the limit of its motion being indicated by dotted lines in Fig. 2. The lever t is jointed to the lever s by the screw w , Fig. 3, and the upper extremity of lever t is attached to the handle x of lever s by the link y , Figs. 1 and 3.

The handle x is loose on the shank of the lever s , and is capable of an alternating free motion on said shank, and through link y it imparts an alternating motion to the lever t , and through it to the wheel z , for the purpose of throwing this wheel on and off its work.

z is an imitation-stitch wheel, such as is usually operated by hand, except that this 40 wheel z is constructed with a rounded bevel, a^2 , Fig. 5, on the side which in the operation of the machine comes next the upper of the boot or shoe.

The wheel z is attached to the lower end of 45 the lever t and arranged at such an angle with

relation to the upright roller b^2 , Figs. 1 and 6, that the faces of the wheel-teeth shall be parallel with the axis of the roller b^2 .

A spiral spring, (not shown,) one end of it being attached to the lever s and the other end caused to press against the top end of lever t , may be employed, if desired, to throw the lever t out automatically, leaving it to the operator to produce only the opposite motion.

c^2 , Figs. 1 and 6, is a gage, adjustable by means of the screw d^2 . The office of this gage is to regulate the breadth of the marginal space—that is to say, the distance between the line of imitation-stitches and the edge of the sole—and cause said space to correspond with the impression produced by the lip of the burnishing-iron on the edge of the boot or shoe sole, thus permitting the part of the sole-edge which is not impressed with the fair-stitch to be burnished.

In using the fair-stitching mechanism in connection with the burnishing-head the operator, grasping with his right hand the handle m and with his left hand the handle x , 70 throws the impression-wheel z back from the roller b^2 by turning the handle x . He then inserts the edge of the sole between the impression-wheel z and the roller b^2 , resting said edge on the gage c^2 . He then clamps the 75 wheel and roller together against the sole by turning back the handle x . The shoe is then moved forward by jack mechanism, (not shown,) the operator keeping the sole clamped and guiding the wheel so as to make it conform to the varying curves and bevels of the sole-edge, at the same time oscillating the handle x back and forth on the pivot u , as may be required to keep the wheel z in line with its work.

The fair-stitching mechanism may be fastened to a bench or table and used apart from the burnishing-head.

We claim—

1. The impression-wheel z , constructed with

the rounded bevel a^2 , for producing imitation fair-stitches without injury to the boot or shoe upper, substantially as set forth.

2. The combination of the levers s and t ,
5 the alternating handle x , and the link-joint y with the impression-wheel z , the roller b^2 , and the gage c^2 , for throwing the wheel z off and on its work and producing imitation fair-stitches, substantially as set forth.

- 10 3. The beveled impression-wheel z , set at an

angle with respect to the roller b^2 , in combination with the adjustable gage c^2 and the roller b^2 , for producing imitation fair-stitches, substantially as set forth.

BENJ. J. TAYMAN.
JOSEPH BENNOR.
